his attorney.

UNITED STATES PATENT OFFICE.

KARL PAUL GOTTSCHALK, OF DRESDEN, GERMANY, ASSIGNOR TO HENRY STAIER,
OF GRUNAU, NEAR BOSSWEIN, SAXONY, GERMANY.

APPARATUS FOR SUPPLYING COLOR TO VERTICAL STAMPING ROLLERS.

Application filed March 25, 1922. Serial No. 546,943.

To all whom it may concern:

Be it known that I, KARL PAUL GOTTSCHALK, engineer, a subject of the Republic of Saxony, German Republic, and resident of 5 19 Reickerstrasse, Dresden, Republic of Saxony, German Republic, have invented a new and useful Apparatus for Supplying Color to Vertical Stamping Rollers, of which the following is a specification.

- 10 The present invention has for its object an apparatus for transmitting or supplying color or liquid color from a horizontally arranged color-box onto a vertical stamping-roller rotating on a vertical shaft. For this purpose the color or liquid color is removed 15 from the horizontally arranged color-box by rollers or cylinders rotating on horizontal shafts and transmitted or supplied to or onto the lateral or front surface of a disc 20 rotating on a horizontal shaft or onto the periphery of a conical disc or roller by the contact of the transmitting roller proper with the surface of the disc, said contact being maintained in a horizontal plane laid 25 through the rotary shaft, or with the slanting surface of the conical disc or roller. The color or liquid color transmitted or supplied to the surface of the disc in the manner described is removed from the surface of the 30 disc by a roller or cylinder rotating on a vertical shaft, said roller or cylinder being in contact with the upper or lower part of the surface of the disc in the vertical plane laid through the shaft. The color or liquid 35 color is thereafter transmitted or supplied from said roller onto the stamping-roller.

The object of the present invention is represented in the drawing annexed as an example of construction. Fig. 1 is a longitudinal elevation, Fig. 2 a plan and Fig. 3 a front elevation.

a is the color-box horizontally arranged, *b* a transmission roller closing the one side of said box in such a manner that the roller *b* removes the color or liquid color from said 45 box *a*. *c* is also a transmission-roller rotating on a horizontal shaft. The color or liquid color received is transmitted or supplied by the roller *b* onto said roller *c*. *d* is a disc rotating on a horizontal shaft and being in contact by its lateral or front surface with the roller *c* in a horizontal plane laid through the horizontal shaft of said 50 roller *c* so as to transmit or supply the color from the roller *c* onto the surface of the disc

d. *e*¹ or *e*² is a roller rotating on a vertical shaft and being in contact with the upper or lower part of the disc *d* in such a manner that the roller *e*¹ or *e*² is situated at 90 or 270 degrees in face of the roller *c* and the color is transmitted or supplied from the surface of the disc *d* onto the roller *e*¹ or *e*². From said roller the color is transmitted for instance by means of an intermediate roller *f* to a stamping roller *g* or the like.

In the manner described it is possible to transmit the color or liquid color by rollers and a disc or roller from a horizontally arranged color-box onto a vertically or obliquely arranged stamping-roller or rollers 70 rotating on a vertical or oblique shaft.

What I claim is:

1. In an apparatus for transmitting or supplying color or liquid color from a horizontally arranged color-box onto a stamping-roller vertically arranged and rotating on a vertical shaft, the combination with said box and stamping-roller, of means for supplying the color or liquid color from said box in a vertical plane, means for supplying said color or liquid color in a vertical plane perpendicular to the vertical plane first mentioned and means for supplying the color or liquid transmitted in a horizontal plane towards and onto the stamping roller. 80

2. In an apparatus for transmitting or supplying color or liquid color from a horizontally arranged color-box onto a stamping-roller vertically arranged and rotating on a vertical shaft, the combination with said box and stamping roller, of transmission rollers rotating on horizontal shafts, a disc rotating on a horizontal shaft and receiving the color from the rollers on its lateral or front surface, a roller receiving 90

on its periphery the color or liquid color transmitted through the disc rotating on a shaft and means for transmitting the color from the roller last mentioned to the stamping-roller.

3. In an apparatus for transmitting or supplying color or liquid color from a horizontally arranged color-box onto a stamping-roller vertically arranged and rotating on a vertical shaft, the combination with said box and stamping roller, of transmission-rollers rotating on horizontal shafts, a disc rotating on a horizontal shaft and receiving the color from the transmission rollers on its lateral or front surface, a 100

roller receiving on its periphery the color transmitted through the disc rotating on a shaft and situated in a vertical plane laid through the shaft of the disc and an intermediate roller transmitting the color from the roller first mentioned onto the stamping roller, one of the transmission-rollers rest-

ing against the lateral or front surface of the disc and being situated in a horizontal plane laid through the shaft of the disc. 10

In testimony, that I claim the foregoing as my invention, I have signed my name this nineteenth day of May, 1923.

KARL PAUL GOTTSCHALK.
